UNITED STATES PATENT OFFICE.

JAMES C. WALLACE, OF DENVER, COLORADO.

RAILWAY-RAIL JOINT.

1,132,232.

Specification of Letters Patent. Patented Mar. 16, 1915.

Application filed February 25, 1914. Serial No. 820,800.

To all whom it may concern:

Be it known that I, JAMES C. WALLACE, citizen of the United States, residing at the city and county of Denver and State of Colorado, have invented certain new and useful Improvements in Railway - Rail Joints; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in railway rail joints, my object being to provide a joint of this class which shall be exceedingly simple in construction, reliable, and efficient in use.

20 My improved joint consists of a metal member adapted to receive the adjacent extremities of the rail, the metal member being so constructed as to embrace both the base and web of the adjacent rail extremities.

25 The central portion of the device, between the ends of the rails employed to form the joint, is equipped with an abutment of the same size and shape as the rails, and against which the extremities of the rails abut.

30 The device as shown in the drawing is equipped with a removable angle-shaped member which, when the parts are assembled, engages one of the rails on one side, being secured in place by suitable fastening 35 devices. This angle member is placed in position and displaced by a longitudinal movement, as the base of the device constituting the joint is provided with a rib or lip which prevents the movement of the removable member in a lateral direction.

40 The integral metal device included in the joint has relatively large openings formed in its upper members, whereby the heads of the fastening devices may pass therethrough 45 and directly engage the base of the rails in the formation of the joint. However, the openings for the fastening devices in the removable member are of less area, and do not permit the heads of the fastening devices to pass through, since these fastening devices must be relied upon to maintain the removable angle-member in place.

50 Having briefly outlined my improved construction, I will proceed to describe the same in detail, reference being made to the

accompanying drawing, in which is illustrated an embodiment thereof.

In this drawing,—Figure 1 is a top plan view of a rail joint of my improved construction. Fig. 2 is a similar view, with the removable part of the joint displaced. Furthermore, in this view only one of the rail extremities is illustrated. Figs. 3, 4, and 5 are cross-sections taken on the lines 3—3, 4—4, and 5—5, respectively, of Fig. 1. Fig. 6 is a perspective view of the body member of the joint, shown in detail. Fig. 7 is a similar view of the detachable member.

The same reference characters indicate the same parts in all the views.

Let the numeral 5 designate what I will term the body member of my improved rail joint. This member consists of a bed plate 6 which is provided on one side with an angle part 7, which is first bent, as shown at 8, at the outer edge of the bed plate, and pressed down closely upon the said bed plate, as shown at 9. This part 9 extends inwardly to engagement with the outer edge 80 of the base 10 of the rail on one side. From this point 12, the part 7 extends upwardly, as shown at 13, in an inclined plane conforming to the inclination of the base of the rail. The inner extremity of the part 13 extends to the web 14 of the rail, and from this point 15 the angle member extends upwardly in engagement with the web of the rail on one side, as shown at 16. On one side the angle member 7, which has just 85 been described in detail, extends the entire length of the bed plate 6, while on the opposite side an angle member 17 of substantially the same construction extends a little more than half of the length of the bed 90 plate. The various parts of the angle members 7 and 17 are substantially identical, and may be given corresponding reference characters. The vertical rail-web-engaging part 16 of the two members 7 and 17 are 95 spaced, as shown at 18, to receive the web of the rail at one end of the device; the rail extremity being inserted in an endwise direction.

100 Centrally located of the body of the joint is an abutment 19, as indicated in the drawing, which is formed integral with the body of the device, and is in the path of the extremities of the rails, which approach each other to form the joint. The rail ends re- 110

spectively abut against the opposite extremities of the abutment 19 when the parts are assembled to form the joint.

At one extremity the body member 5 is open on one side a distance equal to the length of the portion of one rail which is employed in forming the joint. When the parts are assembled, this space is occupied by an angle-shaped member 20 which is provided with a vertical web-engaging part 21, a part 22 adapted to engage the base of the rail on one side, and an offset 23 adapted to engage the outer edge of the rail base. Beyond the offset 23, the angle member 20 is provided with a horizontally disposed part 24 which extends outwardly into abutting relation with the inner surface of a rib or lip 25, against which the outer edge 26 of the angle member 20 fits closely. By virtue of this construction, the member 20 must be inserted in an endwise direction when the parts are assembled, to form the complete joint. By virtue of the employment of this removable member 20, it becomes practicable to remove one rail of the joint, and substitute another rail, since when the angle member 20 is displaced, the rail to be removed will be permitted first sufficient lateral movement to remove it from the line of the joint, after which it may be moved longitudinally a sufficient distance to displace it from the opposite joint.

In the parts 9 and 13 of the angle portions of the body of the joint, are formed relatively large openings 27 which are of sufficient size to permit the heads 28 of the bolts, lock screws, or other suitable fastening devices, to pass therethrough and engage the outer edge of the base of the rail. By virtue of this construction, the heads 28 of the fastening devices are adapted to bear directly upon the bases of the rails, whereby the latter are more securely held in place, both against longitudinal and lateral movement. The lateral movement is prevented by reason of the fact that the shanks of the fastening devices occupy positions in engagement with the outer edges of the flanges of the base of the rail.

The removable angle member 20 is provided with openings 29 adapted to receive the shanks 30 of the fastening devices 31. These openings are not large enough to per-

mit the heads of the fastening devices to pass therethrough. These heads are relied upon to maintain the angle member 20 in its proper relative position in the formation of the joint. Both sets of fastening devices 28 and 31 pass through registering openings in the bed plate 6, and enter the ties 32, 60 which may be of any suitable construction. In the drawing it is assumed that these ties are composed of wood.

Where my improved joint is used in connection with electric railway systems, in which the electric current passes through the rails, I equip the bed plate 6 with copper rivets 33 on opposite sides of the center of the joint, beyond the abutting ends of the rails. By virtue of the location of these copper rivets, the rails may be forced tightly against the same, and the current will pass readily through the bed plate from one of these rivets to the other, thus bridging the spaces between the adjacent extremities of the rails, and rendering an interruption of the circuit at these points impossible.

Having described my invention, what I claim is:

A railway rail joint, comprising a device shaped to conform to the shape of the base and web of the rail ends to be joined, and open at both ends to receive the rails, the said device being composed of two members, namely, a body member and a removable angle member, the latter being of a length equal to that of one of the inclosed rail ends, the bed plate of the body of the device extending underneath the angle member and having a rib at its outer edge which the outer edge of the removable angle member engages, the body of the device having a centrally located, fixed abutment conforming to the general shape of the abutting rail ends, the said device having top and bottom openings to receive headed fastening devices, certain of the top openings being large enough to allow the heads of the fastening devices to pass therethrough into engagement with the base of the rail.

In testimony whereof I affix my signature in presence of two witnesses.

JAMES C. WALLACE.
